UNITED STATES PATENT OFFICE.

FRANK N. FORSTER, OF BUFFALO, NEW YORK.

PAPER BOX.

SPECIFICATION forming part of Letters Patent No. 358,806, dated March 1, 1887.

Application filed January 19, 1886. Serial No. 189,100. (No model.)

To all whom it may concern:

Be it known that I, FRANK N. FORSTER, of the city of Buffalo, in the county of Erie and State of New York, have invented new and useful Improvements in Paper Boxes, of which the following is a specification.

This invention relates more particularly to that class of paper boxes which are designed for holding matches, and has for its object to construct a paper box in which matches can be packed for the trade, and which can be readily converted into a match-safe, from which the matches are removed as they are required for use.

15 My invention consists, to that end, in the particular construction of the paper box, as will be hereinafter fully set forth, and pointed out in the claims.

In the accompanying drawings, Figure 1 represents a perspective view of my improved box in the position in which it is used as a match-safe. Fig. 2 is a similar view showing the box filled with matches and having its lid or cover closed. Fig. 3 is a plan view of a blank from which my improved box is formed. Fig. 4 is a fragmentary perspective view of a modified construction of the box.

Like letters of reference refer to like parts in the several figures.

30 A represents the blank of paper or paper-board, which is cut to the required shape for forming my improved match-box. The body of the box, which is formed from the blank A, consists of a back or bottom portion, b, an end portion, c, two side portions, d d, and two front or face portions, e e. The bottom or back b is formed from the center of the blank A, and the end portion, c, is formed from a continuation of one end of the portion b, by folding or bending the blank on a transverse line, f, drawn across the blank A near one end thereof. The sides d d are formed by folding the blank on the longitudinal lines g g, which are drawn parallel with each other on opposite sides of the bottom portion, b, and which form the dividing-line between the bottom and sides of the box. The front or face portions, e e, form continuations of the side portions, d d, and are formed by folding the blank on the lines h h, which are drawn parallel with the lines g g, and at the point of division between the sides and the front of the box.

i i are two corner-pieces formed on one end of each front portion, e e, by the bend or fold of the blank on the line f. When the blank 55 has been folded to the position to form a box, as shown in Fig. 1, the corner-pieces i i will rest upon the end portion, c, and by cementing these parts together by glue or other suitable adhesive material the parts forming the 60 body of the box will be held firmly in position.

j j are small end flaps formed at one end of the side portions, d d, and resting upon the corner-pieces i i when the parts are folded, as 65 shown in Fig. 1. The flaps j are glued to the flaps i, and serve to strengthen the sides of the box.

K represents a longitudinal slot formed in the front or face of the box between the two 70 front portions, e e, and which extends the entire length of the body of the box. The front portions, e e, at the top of the box are connected together by a cross-strip, l, which may be made of the same material of which the 75 box is formed, and cemented or glued to the face portions e e, as shown in Figs. 1 and 2; or, if desired, a strip of metal may be employed by folding and clamping the same over the edges of the portions e e, as shown in 80 Fig. 4.

N represents the top or cover of the box. The cover N forms a continuation of the portion b, and is formed by folding the blank on the transverse lines o o'. The cover N is made 85 longer than the thickness of the box, and is provided at its outer end with an extension, n, which is adapted to be inserted under the cross-strip l and front portions, e e, when the cover is closed, as shown in Fig. 2. 90

p p are small end flaps formed on the side portions, d d, and provided with straight edges p', so that when the flaps p are folded on the line o the edges p' will stand parallel and adjacent to the front portions, e e. When the 95 cover N has been closed and its extension n inserted under the front portions, e e, the straight edges p' of the end flaps, p, will bear against the cover and retain it in place.

The cover N is provided with a suitable eye-let-hole, q, whereby the box can be hung upon a hook, r, when it is desired to be used as a match-safe, the matches being readily removed therefrom as required by inserting the

finger through the longitudinal slot or opening K and raising the matches to the top of the box.

By packing the matches in the box as shown 5 in Fig. 2 the ends of the matches are protected by the portions *e e*, which form the face or front portion of the box.

I am aware a box or match-safe having a vertical opening in its front, through which 10 the matches are exposed, is not new, and I do not broadly claim such construction.

I claim as my invention—

1. A paper box formed of a single blank containing a back portion, *b*, side portions, *d*, 15 front portions, *e e*, formed at the outer edges of the side portions, *d*, and made of less aggregate width than the back *b*, to leave an opening, *K*, a bottom piece, *C*, and a cover, *N*, formed at opposite ends of the back *b*, and 20 a cross-piece, *l*, connecting the upper ends of the front pieces, *e*, substantially as set forth.

2. A paper box for matches, composed of a back portion, *b*, end portion, *c*, side portions, *d d*, and front portions, *e e*, the sides *d* and portions *e* being secured to the end portion, *c*, 25 by flaps *i* and *j*, a cross-piece, *l*, connecting the upper ends of the front portions, *e e*, a longitudinal slot, *K*, extending the length of the box and arranged centrally between the front portions, *e e*, and a cover, *N*, provided with 30 an eyelet-hole, *q*, and adapted to engage under the front portions, *e e*, substantially as set forth.

Witness my hand this 13th day of January, 1886.

FRANK N. FORSTER.
